BADGE READER HOUSING OR SIMILAR ARTICLE

Jack W. Stringer, Los Gatos, Calif., assignor to International Business Machines Corporation, New York, N.Y., a corporation of New York

Filed Oct. 25, 1960, Ser. No. 62,617

Term of patent 14 years

(Cl. D26—5)

FIG. 1

FIG. 2

FIG. 3

FIG. 5

FIG. 4

FIG. 1 is a rear perspective view of a badge reader housing or similar article showing my new design.

FIG. 2 is a front elevation of the same.

FIG. 3 is a top view of the same.

FIG. 4 is a left side elevational view of the same, the opposite side being substantially similar in appearance.

FIG. 5 is a front perspective view thereof.

The dominant feature of my new design is an upper substantially horizontal surface having a badge receiver opening near the front edge of the top surface, a pair of push button type control switches one at each end of the badge receiver opening, and a prism shaped display panel

for a plurality of status indicating lights protruding from the top surface near the rear edge.

I claim:

The ornamental design for a badge reader housing or similar article, as shown and described.
